UNITED STATES PATENT OFFICE

CUTLER D. KNOWLTON, OF REVERLY, MASSACHUSETTS, ASSIGNOR TO HOAGUE-SPRAGUE CORPORATION, OF LYNN, MASSACHUSETTS, A CORPORATION OF MASSACHUSETTS

ART OF BOX MAKING

Application filed August 29, 1927. Serial No. 216,220.

This invention relates to the art of making boxes, being specially concerned with a method of producing a smooth, finished edge where the box-material is divided, as at the 5 corners of the box. The novel features embodied in the blank and box illustrated and described herein as produced by carrying out this method are made the subject of a divisional application in my name filed in the 10 United States Patent Office on February 10, 1930, with the Serial No. 427,206.

When boxes of the type disclosed in Patent No. 1,476,549, Smith, December 4, 1923, and consisting of a pasteboard shell covered 15 with paper, are made by assembling the shell-material and cover-material before the boxes are set up, there are left exposed, unless precautions are taken to hide them, unsightly strips of shell-material. This may occur, for 20 example, at the vertical edges of the wings which overlie the corner-laps at the ends of the boxes.

An object of the invention is to attain, by 25 a simple procedure, an effective concealment of the shell-edges. To this end, the sheet from which the blank and the resulting box are to be formed is cut or scored at opposite sides, divided in a plane joining the cut lines to give a reduced marginal extension, and 30 such margin bent and secured to an adjacent surface of the sheet. In the production of the blank the margin may or may not be thus attached, in the preferred form of the invention it being secured to an adjacent wall of 35 the box when this is set up. Herein, I provide for the assembling of the shell or body-material with the cover-material, the scoring of these upon lines spaced transversely of the assembled sheet, as at the meeting of the end 40 wings and corner-laps, and the splitting of the shell-material between the scores. When the resulting blank is set up into box-form, the inner face of the split margin upon an end wing is preferably secured to the adjacent side wing, with the cover-material exposed and the raw edge of the shell almost entirely concealed. At the same time, this 45 attached marginal extension acts as a stay for the box-corner at the meeting of the side and end wings.

In the accompanying drawings, Figs. 1 and 2 suggest, diagrammatically and in perspective, apparatus by which my improved method may be carried out;

Fig. 3 is an enlarged transverse section 55 through the scoring mechanism;

Fig. 4 is an enlarged longitudinal section through the splitting mechanism;

Fig. 5 shows the forming mechanism in its initial position;

Fig. 6 is a perspective view of a portion of a box formed by the present method; and

Fig. 7 is a similar view of a modification of such box. When here and elsewhere in the specification a box is referred to, it is to 65 be understood that the invention applies as well to the production of box-covers as to the bodies.

In making the box of Fig. 6 by a continuous-production method, I prefer, though it 70 is not essential to the success of the invention,

to advance a web of pasteboard A or other material suitable for the box-shell, this web being mounted upon a spindle 10, while adjacent to it a web of such cover-material B as 75

paper is arranged to turn upon a spindle 12. Glue or other appropriate adhesive is applied to the inner face of one of the webs, as B, by a device 14, after which said webs are 80

assembled by being pressed together and are advanced by a pair of rolls 16, 16. The cover-web may be somewhat wider than the shell-web and is shown as turned over at a and forced against the under side of the shell, which is at the inside of the box, by opposite 85

folding abutments 18, but one of which is shown. By a mechanism 20 the assembly is provided with longitudinal creases b, b, which mark the junctures of the box-bottoms 90

c and side wings d and between the end wings e and the corner-laps f. A mechanism 22 creases the assembly transversely at g, thus defining the successive lines between the bottoms c and end wings e and between the side 95

wings d and the corner-laps f. By a roll mechanism 24 each box-section of the assembly is scored at its opposite sides. At the lower or shell-side, arcuate knives 26, 26 carried by the under roll of the pair cut lines 100

h, preferably substantially coinciding with

the crease-lines b and extending along the junctures between the end wings and corner-laps of adjacent sections. At the same time, the upper or cover-paper side is scored by 5 circumferential knives 28, 28 somewhat separated from the knives 26 transversely of the sheet. The lines i , i thus cut are spaced outwardly from the lines h , to which they are parallel. At their adjacent ends, each line 10 i is joined to the vertical plane through the companion line h by an inclined line j which is scored in the material by a knife 30. At its opposite or outer end, each line i is shorter than the corresponding line h , and 15 here an inclined score-line k connects the lines i and h , being produced by a knife 32. The lines j and k which are on the same corner-lap converge outwardly to the line i which connects them. The bottoms of all 20 these scores terminate in a common plane l parallel to the outer faces of the sheet. In the present instance, this plane is shown as about one-third of the distance through the assembly from the cover-paper side. As will 25 hereafter appear more clearly, there may be conditions which call for a change in the relation between the depths of the scores. After being scored, the assembly is acted upon by cutting mechanism 34, which divides 30 it into individual box-blanks C, the separation occurring along transverse lines m passing through the junctures of the scores j . The blanks thus divided are shown as accumulated in a stack within a receiver 35 36.

The blanks may now have the corner-laps separated from the end wings to which they are connected, at the same time there being a marginal extension of reduced thickness created upon each extremity of the end wing. A means for effecting this is illustrated in connection with the setting-up apparatus of Fig. 2. The blanks, in a direction at right angles to that which they followed in the assembling operation, are advanced between opposite pairs of rotatable rolls 38 and 40. Each roll 38 has a pair of projections 42, so arranged that in connection with a registering depression in the corresponding bed-roll 45 50 55 60 65 70 75 80 85 90 95 100 105 110 115 120 125 130 135 end wing with its vertical edges fully finished, with only cover-paper exposed, and also giving a uniform thickness of the wing, so that its surface is smooth throughout.

Having described my invention, what I claim as new and desire to secure by Letters Patent of the United States is:

1. The improvement in the art of making boxes which consists in cutting opposite sides of a sheet, dividing the sheet in a plane joining the cut lines to form a reduced margin, and bending said margin and securing it to an adjacent surface of the sheet.

2. The improvement in the art of making boxes which consists in cutting opposite sides of a sheet along lines spaced from each other and along connecting lines, dividing the sheet in a plane joining the cut lines to form a reduced margin, and bending such margin and securing it to an adjacent surface of the sheet.

3. The improvement in the art of making boxes which consists in cutting opposite sides of a sheet, the cuts terminating in a plane substantially parallel to the surfaces of the sheet, dividing the sheet in a plane joining the cut lines to form a reduced margin, and bending said margin and securing it to an adjacent surface of the sheet.

4. The improvement in the art of making boxes which consists in applying to a side of a sheet a finish-surface, cutting opposite sides of the sheet, dividing the sheet in a plane joining the cut lines to form a reduced margin, and bending such margin and securing it with the finish-side out to an adjacent surface of the sheet.

5. The improvement in the art of making boxes which consists in cutting opposite sides of a sheet, the cuts terminating in a plane substantially parallel to the surfaces of the sheet and nearer one of said surfaces than the other, dividing the sheet in a plane joining the cut lines to form a reduced margin, and bending said margin and securing it to an adjacent surface of the sheet.

6. The improvement in the art of making boxes which consists in securing together a sheet of shell-material and a sheet of cover-material, scoring through the cover-material into the shell-material, scoring the side of the shell-material opposite the cover-material, the scores being spaced from each other transversely of the sheet, dividing the shell-material in a plane joining the scored lines to form a reduced margin, and bending and securing such margin with the shell-material concealed.

7. The improvement in the art of making boxes which consists in securing together a sheet of shell-material and a sheet of cover-material, scoring through the cover-material into the shell-material along a straight line, with lines converging toward each other at the ends of the straight line, scoring the side

of the shell-material opposite the cover-material along a line connecting the inner extremities of the converging lines, dividing the shell-material in a plane joining the scored lines to form a reduced margin, and bending and securing such margin with the shell-material concealed.

8. The method of making boxes which consists in scoring opposite sides of a sheet of box-material along separated lines, dividing the sheet between the scored lines to form a reduced margin, setting up the sheet in box-form, and securing the reduced margin to an adjacent surface.

9. The method of making boxes which consists in scoring opposite sides of a sheet of box-material along separated lines, dividing the sheet between the scored lines to form a reduced margin extending from the edge of one wall, setting up the sheet in box-form, and securing the reduced margin to the adjacent wall.

10. The method of making boxes which consists in creasing sheets of box-material to furnish fold-lines, scoring opposite sides of the sheets, dividing the material between the scored lines to form reduced margins, bending the material at the creases into box-form, and securing the reduced margins to the adjacent walls of the box.

11. The method of making boxes which consists in securing together a web of shell-material and a web of cover-material, creasing the assembly to furnish fold-lines, scoring opposite sides of the assembly, the resulting scores terminating in a plane within the shell-material, cutting the assembly into discrete blanks, dividing the material between the scored lines to form reduced margins including cover-material in the outer faces, bending the blanks at the creases into box-form, and securing the reduced margins to the adjacent walls of the box with the cover-material exposed.

12. The method of making boxes which consists in cutting a sheet of box-material at opposite sides along lines separated transversely of the sheet, splitting the material between the cuts, and setting up the box with the split portions included in its walls.

13. The method of making boxes which consists in cutting a sheet of box-material at opposite sides along lines separated transversely of the sheet, splitting the material between the cuts, and setting up the box with one of the split portions included in one of the side walls and the other split portion included in an adjacent wall.

14. The method of making boxes which consists in creasing box-material to define the bottom, side and end wings and corner-laps, scoring the inner side of the material at the junctures of the end wings and corner-laps, scoring the outer side of the material between the first-mentioned scored lines and the op-

posite edges of the corner-laps, splitting the material between the scored lines to separate the end wings and the corner-laps, and setting up the box.

15. The method of making boxes which consists in creasing box-material to define the bottom, side and end wings and corner-laps, scoring the inner side of the material at the junctures of the end wings and corner-laps, scoring the outer side of the material between the first-mentioned scored lines and the opposite edges of the corner-laps, splitting the material between the scored lines to separate the end wings and the corner-laps to form reduced end-wing extensions, and setting up the box with the end-wing extensions secured to the side wings.

16. The method of making box-blanks which consists in cutting a sheet of box-material at opposite sides along lines separated transversely of the sheet, and dividing the sheet in a plane joining the cut lines.

17. The method of making box-blanks which consists in cutting a sheet of box-material at opposite sides along lines separated transversely of the sheet and along additional lines connecting the separated lines at one side of the sheet, and dividing the sheet in a plane joining the cut lines.

18. The method of making box-blanks which consists in creasing a sheet of box-material to furnish fold-lines, scoring the sheet at one side along a crease, scoring the opposite side of the material along a line adjacent the crease, and splitting the material between the scores.

19. The method of making box-blanks which consists in creasing a sheet of box-material to furnish fold-lines, scoring the sheet at one side along a crease, scoring the opposite side of the material along a line adjacent the crease and along the lines converging from the extremities of said line, and splitting the material between the scores.

20. The method of making box-blanks which consists in securing together a sheet of shell-material and a sheet of cover-material, scoring the assembly through the cover-material into the shell-material, scoring the side of the shell-material opposite the cover-material, and splitting the material between the scores.

21. The method of making box-blanks which consists in securing together a sheet of shell-material and a sheet of cover-material, creasing the assembly to furnish fold-lines, scoring the assembly through the cover-material into the shell-material adjacent a crease-line, scoring the side of the shell-material opposite the cover-material at a crease, and splitting the material between the scores.

22. The improvement in the art of making boxes which consists in cutting opposite sides of a sheet, dividing the sheet in a plane join-

ing the cut lines to form a reduced margin, and bending said margin and securing it to its adjacent portion.

23. The method of making boxes which consists in scoring opposite sides of a sheet 70 of box-material along separated lines, dividing the sheet between the scored lines to form a reduced margin, doubling the reduced margin upon itself, and setting up the sheet in box-form.

24. The method of making boxes which consists in creasing box-material to define the bottom, side and end wings and corner-laps, scoring the inner side of the material at the junctures of the end wings and corner-laps, scoring the outer side of the material between the first-mentioned scored lines and the opposite edges of the corner-laps, splitting the material between the scored lines to separate the end wings and corner-laps to 80 form reduced end-wing extensions, doubling the end-wing extensions upon themselves, and setting up the box.

25. The method of making box-blanks which consists in cutting a sheet of box-material 90 at opposite sides along lines separated transversely of the sheet, dividing the sheet in a plane joining the cut lines, and doubling upon itself one side of the material divided along each line.

26. The method of making box-blanks which consists in cutting a sheet of box-material at opposite sides along lines separated transversely of the sheet to separate end wings and corner-laps, dividing the sheet in a 100 plane joining the cut lines to produce extensions from the end wings and corner-laps, and doubling the end-wing extensions upon themselves and securing them in place.

In testimony whereof I have signed my 105 name to this specification.

CUTLER D. KNOWLTON.
